UNITED STATES PATENT OFFICE.

PALMER COX, OF NEW YORK, N. Y.

DESIGN FOR A BOOK-COVER.

SPECIFICATION forming part of Design No. 24,046, dated February 19, 1895.

Application filed January 19, 1895. Serial No. 535,563. Term of patent 14 years.

To all whom it may concern:

Be it known that I, PALMER COX, a citizen of the United States, residing in the city, county, and State of New York, have invented 5 and produced a new and original Design for Book-Covers, of which the following is a specification.

The leading feature of my design consists in a book-cover ornamented substantially as 10 represented in the accompanying drawings, forming part hereof, which show a book-cover embodying my design, the front thereof being shown in Figure 1, and the back in Fig. 2.

In the drawings, (Fig. 1,) *a a* represent pedestals surmounted by brownie-like figures *b b*, 15 between which is stretched a curtain *f*, over the edge of which peer series of brownie-like

faces *c c c c*. Near the base of each pedestal *a* is a brownie-like figure *d e*, one of which is in a standing and the other in a sitting posture.

In Fig. 2, which represents the back of the book-cover, *a'* indicates a sign-board which is set up in a landscape and flanked on one side by brownie-like figures *b' b'*. There are also 25 brownie-like figures *d' d'* in the foreground.

What I claim is—

The design for a book-cover, substantially as herein shown and described.

PALMER COX.
